[57] CLAIM

The ornamental design for a rappelling device for descending on a rope, as shown and described.

DESCRIPTION

FIG. 1 is an environmental view of a rappelling device for descending on a rope showing my new design;

FIG. 2 is a front elevational view with the rear view being a mirror image thereof;

FIG. 3 is a top plan view thereof;

FIG. 4 is a bottom plan view thereof; and,

FIG. 5 is a right side elevational view with the left side being a mirror image thereof.

The broken line showing of the rope and carabiner in FIG. 1 is for illustrative purposes only and forms no part of the claimed design.
